UNITED STATES PATENT OFFICE.

FLORA ADAMS DARLING, OF NEW YORK, N. Y., ASSIGNOR TO J. E. CALDWELL & CO., OF PHILADELPHIA, PENNSYLVANIA.

DESIGN FOR A BADGE.

SPECIFICATION forming part of Design No. 25,909, dated August 11, 1896.

Application filed May 12, 1896. Serial No. 591,296. Term of patent 14 years.

To all whom it may concern:

Be it known that I, FLORA ADAMS DARLING, a citizen of the United States, and a resident of New York city, New York, have invented 5 a certain new and useful Design for a Badge, of which the following is a specification.

My design for a badge is clearly indicated in the accompanying drawings, in which—

The essential feature of the design is the combination of the star and anchor.

As seen by the accompanying drawings the 15 pendant consists of a five-pointed star having a beaded border and a colored center, and back of this star is a conventional anchor, in which the crown and points as well as the stock are exposed to view from the face of the badge. The pendant is hung from a ribbon of two colors and is secured to a curved pin 20 in the form of a scroll.

I claim—

1. The design for a badge as herein described and as shown in the accompanying drawings.

2. The design for the pendant of a badge, as herein described and as shown in the accompanying drawings.

In testimony whereof I have signed my name to this specification in the presence of 30 two subscribing witnesses.

FLORA ADAMS DARLING.
